UNITED STATES PATENT OFFICE.

JAMES E. GLEASON, OF ROCHESTER, NEW YORK, ASSIGNOR TO THE
GLEASON TOOL COMPANY, OF SAME PLACE.

MACHINE FOR FORMING GEAR-TEETH.

SPECIFICATION forming part of Letters Patent No. 605,249, dated June 7, 1898.

Application filed February 23, 1897. Serial No. 624,557. (No model.)

To all whom it may concern:

Be it known that I, JAMES E. GLEASON, of Rochester, in the county of Monroe and State of New York, have invented a new and useful Improvement in Machines for Forming Gear-Teeth, which improvement is fully set forth in the following specification and shown in the accompanying drawings.

My invention relates to machines for forming the teeth of gears in which rotary toothed cutters are employed; and the invention is designed more particularly for forming the teeth of bevel-gears of comparatively small diameters, but adapted also to form the teeth of spur-gears.

In my improved gear-tooth cutter a cone-center is established and means are provided to set the blank-gear with reference to it and also to give the cutter various motions, including a swinging motion, relating to the cone-center. Means are also provided for rocking the gear while being acted upon by the cutter and for giving the latter lateral intermittent motion during the operation of forming the teeth of a gear. Micrometric adjustments are provided for the cutter and for the rocking of the blank-gear, the machine being designed to form and complete the teeth of a gear at one operation—that is to say, while the blank is turned once around upon its axis or through one complete revolution.

The invention is hereinafter fully described, and more particularly pointed out in the claims.

Referring to the drawings, Figure 1 is a front elevation of my improved machine for forming gear-teeth, some minor parts being omitted. Fig. 2 is a transverse section through the spindle and some associated parts on the line 2 2 in Fig. 1. Fig. 3 is a side elevation of the machine, seen as indicated by arrow 3 in Fig. 1, the door and other parts being omitted and parts broken away. Fig. 4 is a vertical section of parts at the left of the machine, taken on the dotted line 4 4 in Fig. 3 and viewed as indicated by the arrow pointed thereon. Fig. 5 is an elevation of the traveling wheel and arresters, seen as indicated by arrow in Fig. 6, parts being sectioned. Fig. 6 is an elevation of the traveling wheel with some associated parts, a part of the crown-

segment carrier being sectioned away to show the toothed parts. Fig. 7 shows the reverse side of one of the arresters. Fig. 8 is a plan of the lower parts of the machine, the main upper parts and some minor parts being omitted. Fig. 9 is a similar plan with all of the parts above the bracket or knee omitted. Fig. 10 is a cross-section of the column and other parts on the dotted line 10 10 in Fig. 1, showing interior parts. Fig. 11 is a vertical cross-section of the reciprocating bar or reciprocator and some associated parts on the dotted line 11 11 in Fig. 8. Fig. 12 is a side elevation of the toothed reciprocator and rocking wheel with some associated parts. Fig. 13 is an elevation of the reciprocator, rocking wheel, and some of the parts, seen as indicated by arrow in Fig. 12, parts being vertically sectioned. Fig. 14 is a side elevation of the machine, seen as indicated by arrow 14 in Fig. 1, some minor parts being omitted. Fig. 15 is a vertical longitudinal section of the cutter-spindle and other parts, taken on the dotted lines 15 in Figs. 1 and 8, parts being broken away. Fig. 16 shows the interior of the cam-wheel and contained parts, seen as indicated by arrow in Fig. 15. Fig. 17 is a plan of a part of the cutter-carrier and cam-wheel, showing the device for micrometrically adjusting the cutter, parts being horizontally sectioned as on the dotted lines 17 in Figs. 1 and 18. Fig. 18 is a view of a part of the cutter-carrier, cam-wheel, and the micrometric adjusting device, seen as indicated by arrow in Fig. 17. Fig. 19 is a rear elevation of the machine, seen in the direction opposite to that in which Fig. 1 is seen, a part being broken away and some minor parts omitted. Fig. 20 is a view of the spindle-carrier and associated parts, seen as indicated by arrow 20 in Fig. 1, parts being sectioned on the dotted line at the point of the arrow. Fig. 21 is a longitudinal section of the blank-gear spindle and associated parts, taken on the dotted line 21 in Fig. 1, condensed as to length. Fig. 22 shows a portion of the toothed-spindle barrel and the operating-pinion. Fig. 23 is an elevation of the indexing mechanism, seen as indicated by arrow 23 in Figs. 1 and 20, parts being longitudinally sectioned as on the dotted line at the point of the arrow in Fig. 20. Fig. 24 is

an elevation of parts of the indexing mechanism, showing the detent and other parts, parts being sectioned on a plane coinciding with the axis of the operating-crank. Fig. 25 is a longitudinal section of the parts at the right-hand end of the double-pinion shaft, showing the shiftable key for the pinions. Fig. 26 is a transverse section of the parts, taken on the dotted line 26 in Fig. 25. Fig. 27 is a transverse section of the shiftable key through the bit. Fig. 28 is a side elevation of a part of the blank-gear arbor and starting-ring with parts broken away. Fig. 29 is an end view of the arbor and expander with part of a gear in place thereon. Fig. 30 is an elevation of the main parts of the mechanism for rocking the spindle, parts being shown in various positions by full and dotted lines, parts being broken away. Fig. 31 is a rear elevation of parts, showing the back shaft and the manner of holding the same. Fig. 32 is a view of parts, seen as indicated by arrow in Fig. 31, the back shaft being transversely sectioned on the dotted line 32 in Fig. 31. Fig. 33 is a side elevation of a cutter. Fig. 34 is a plan of the cutter-carrier and other parts controlling the cutter, parts being shown in two positions by full and dotted lines. Fig. 35 is an outline plan of parts supported by the knee and other parts above the column, parts being shown in two positions by full and dotted lines. Fig. 36 shows in outline the manner in which the cutter acts upon a gear-tooth. Fig. 37 is a plan in outline, better showing the swinging motion of the cutter. Fig. 38 shows in outline the lateral motion of the cutter. Fig. 39 is an elevation of the main parts of the feed mechanism, parts being shown in two positions by full and dotted lines. Fig. 40 is an elevation of parts of the trip for the feed, parts being sectioned as on the dotted lines 40 in Figs. 14 and 39, parts being shown in two positions by full and dotted lines. Fig. 41 is a view of the under side of the base-block, showing the V-shaped pivot-tongue. Fig. 42 is a skeleton figure showing the relation of various shafts. Fig. 43 is a side elevation of parts of the indexing mechanism, parts being broken away. Fig. 44 is an axial section of the double gear and some associated parts on the dotted line 44 in Fig. 3. Fig. 45 is an elevation of part of the traveling wheel. Figs. 1, 3, and 8 to 10, inclusive, and 12, 14, 19, 31, 32, 35, 41, and 42 are drawn to a scale of about one-sixth full size; Figs. 2, 4, 6, 13, 15, 16, and 20 to 23, inclusive, and 30, 34, 39, 43, and 44 to a scale about one-third size; Figs. 11, 17, 18, 24, 25, 27, and 37 to a scale about one-half size; Figs. 5, 7, and 26 to a scale about two-thirds size, and Figs. 28, 29, 33, 38, 40, and 45 to a scale about full size. Fig. 36 is drawn to an exaggerated scale to show more clearly the matter wished to be brought out.

Referring to the parts shown, A in the various figures is a hollow prismatic column of iron adapted to stand upright upon the floor B, which column acts as a frame for support-

ing the operating parts of the machine. The column is formed at its base with a horizontally-extended part F, giving breadth to the base and for other purposes.

C, Figs. 1, 9, and 14, is a horizontal knee or bracket for supporting the cutter and other parts, adapted to move in vertical directions along ways D upon a face of the column. This bracket is supplied with a gib a, contiguous with the ways D and held by set-screws b.

E is a vertical screw, preferably formed with a square thread four to the inch, for controlling the bracket. This screw is headed in a shelf c of the bracket, as appears in Figs. 14 and 19, with set-nuts d above the shelf to hold it in place, the nut e for the screw resting in the part F of the column.

G is a curved segment of iron secured to the upper horizontal end or top of the column by bolts f, Figs. 3 and 19. This segment overhangs the top of the column and projects over the bracket C and the extended part F of the column.

H, Figs. 1, 14, and 20, is a spindle-carrier adapted to move along the vertical plane face of the segment G, concentric grooves g and h being formed in the face of the segment to guide the carrier in its movements therealong. The grooves or races g and h are concentric with the cone-center of the machine, and the carrier H constitutes a holder for the various parts controlling the blank-gear and the blank-gear itself.

I, Figs. 1, 2, 3, 20, and 21, is a spindle for carrying the blank-gear K to be cut, the spindle being held in a spindle-barrel L, supported in the spindle-carrier H.

N, Figs. 1, 8, 14, 15, 18, and 34, is a cutter-carrier adapted to move longitudinally in a carriage O, the latter being adapted to slide horizontally upon ways i of a base-block P, resting directly upon the bracket C.

The cutter, Fig. 33, which is circular and toothed, is driven by means of a belt running upon a step-pulley R, Figs. 1, 3, and 10, held upon a horizontal shaft S, extending through the lower part of the column and resting in bearings T T, secured to the column.

U, Figs. 1, 9, 10, 14, and 19, is a vertical shaft connected with the shaft S by miter-gears k l, held in bearings m n in the bracket C and the part F of the column, respectively. This shaft is adapted to slide longitudinally through the gear l, the latter being provided with an ordinary feather occupying a groove or spline o in the shaft, so that the shaft and gear must turn together. The shaft is provided at its upper end with a miter-gear p, adapted to drive a horizontal shaft r, Fig. 42, by engaging a miter-gear s on said shaft r. The gear p is bedded in the upper surface of the bracket C, the points of the teeth slightly projecting thereabove. The shaft r extends obliquely across a bearing in the base-block P and is provided at its opposite end with a bevel-gear t.

u is a horizontal back shaft at the side of

the base-block, having a bevel-gear v , engaged by the gear t on the shaft u . The axes of the shafts r and u are in the same horizontal plane, the latter shaft resting in bearings w and x , Figs. 31 and 32, the former bearing being secured to the base-block P and the latter to the carriage O . The shaft u is provided with a gear y , Figs. 19 and 31, which engages a gear V , Figs. 1, 8, 14, 15, 19, and 35. The gear V is rigid with the cutter-spindle W , adapted to turn in the cutter-carrier N . The cutter z , as shown in Fig. 15, is held upon a tapered arbor a' , fitted in the end of the spindle, the cutter being pressed between collars b' b' on the arbor by means of a nut c' , threaded thereon. A key d' , rigid with the arbor and occupying a corresponding cavity in the spindle W , causes the cutter to always turn with the spindle. From this description of parts and their relation with each other the manner in which the cutter is rotated by means of a belt upon the pulley R will be understood.

In forming the teeth of gears of different sizes and diameters it becomes necessary to change the elevation of the bracket C and incumbent parts, including the cutter.

e' , Figs. 1, 14, and 19, is a short horizontal shaft supported in a hanger f' , secured to the bracket, provided at its inner end with a bevel-pinion g' in position to engage a bevel-gear h' , rigid with the elevating-screw E . At its outer end the shaft is reduced and formed to receive a wrench or crank for turning it. i' is a graduated disk rigid with or a part of the hanger f' , and the shaft is formed with a shifttable index k' , having its point traversing the graduated surface of the disk when the shaft is turned, by means of which the elevation of the cutter may be finally adjusted. The disk is divided into one hundred and twenty-five equal parts. Then if the shaft be turned to carry the index over one space, for example, the cutter will be elevated or depressed to the extent of one one-hundred-and-twenty-fifth parts of one-eighth of an inch, or one one-thousandth of an inch, the gear h' and pinion g' being two to one and the screw four to the inch lead. The index is clamped onto the shaft, so as to hold with moderate friction, but so as to be shifted at any time to point to any particular division-mark on the disk.

The cutter is fed against the blank-gear by feeding mechanism which moves the carriage O along the slides or ways i of the base-block P . This is effected by means of the ordinary feed-screw l' , Fig. 8, between the ways, the nut for the screw (not shown) being of ordinary construction and secured to the under surface of the carriage O .

m' , Figs. 1, 8, 14, and 39, is a worm-gear rigid with the overhanging end of the feed-screw, in position to be actuated by a worm n' , turned from the back shaft u . A feed-shaft o' rests in a holder p' at the end of the base-block P , beneath the feed-screw, to the

overhanging end of which shaft is secured a friction-disk r' . The axis of the feed-shaft is horizontal and in the plane of the axis of the back shaft u , the two axes forming a right angle. An extended reduced part of the back shaft in front of the disk r' (see also Fig. 19) holds a friction-ring s' , of rawhide or other yielding material, in position to bear against the face of the friction-disk, as shown. Now when the back shaft is rotated it will cause the feed-screw l' to turn and so move the carriage O , with the cutter, along the base-block P . The friction-ring s' is carried by a suitable holder t' , splined on the back shaft and turning therewith. By means of shifting the friction-ring toward or from the center of the disk r' the feed may be regulated at pleasure.

A tripping device is arranged to stop or throw off the feed after the cutter has passed across the blank-gear. A trip-stud u' , Figs. 1, 8, and 14, is provided to occupy a horizontal dovetail groove v' in the side of the carriage O .

w' is a horizontal trip-rod held in bearings x' x' , projecting from the side of the base-block P . Upon the trip-rod is placed a movable dog y' , adapted to be encountered by the stud u' as the carriage advances. The holder p' is formed with a downwardly-projecting arm d^2 , Figs. 1, 14, 19, and 39, pivoted upon a second arm e^2 , rigid with the base-block P , so as to swing in a vertical plane toward or from the feed-screw, as indicated in Fig. 39. The holder is also provided with a rigid arm z' , Figs. 1, 8, 14, and 39, adapted to receive within an opening a^2 the enlarged end or head b^2 of the trip-rod, as fully shown in Fig. 40. Directly back of the head b^2 is a notch c^2 , adapted to receive the arm z' when the rod is moved longitudinally to bring the notch within said opening in the arm. Normally when the machine is feeding the head b^2 of the rod occupies the opening in the arm and holds the worm n' up against the gear m' and also the friction-disk r' snugly against the friction-ring s' ; but when from the feed motion the stud u' in the carriage O encounters the dog y' on the trip-rod the latter will be moved to the dotted position shown in Fig. 40, allowing the arm z' to drop into the notch c^2 , as above described. The holder p' , with its incumbent parts, drops from gravity when the notch c^2 is presented to the trip-arm, which throws the worm n' away from its gear m' and the disk r' out of contact with the friction-ring s' . (Clearly shown in Fig. 39.) This at once arrests the feed motion and the carriage stops.

To hold the head b^2 normally within the opening a^2 in the trip-arm, a spiral spring f^2 , Figs. 1, 8, and 40, is employed on the trip-rod confined between the outer bearing x' of the rod and a collar g^2 , rigid on the rod. This spring acts to draw the head of the rod into the opening in the arm when presented to the head, and thus hold the feed mechanism in action.

Besides its rotary motion the cutter is given

an alternated lateral or sidewise motion in line with its axis. (Indicated by the full and dotted line positions of the cutter shown in Fig. 38.) This motion of the cutter is effected by means of a cam-wheel h^2 , Figs. 1, 8, 15, and 34, held to turn upon the cutter-spindle W , adjacent to the gear V . The cam-wheel has a continuous circumferential groove i^2 , occupied by a tongue k^2 of a block l^2 . (See Figs. 17 and 18.) The block l^2 is adapted to slide freely upon the carriage O and against the side of the cutter-carrier N and is provided with a threaded stem m^2 , in position to slide freely through a rectangular projecting part n^2 of the carriage O . The stem, which is parallel with the spindle W , is provided with a pair of threaded rings $o^2 p^2$ at one side of the body n^2 and another pair of similar threaded rings $r^2 s^2$ at the opposite side of said part n^2 . These pairs of rings are adapted to be turned on the stem up against the part n^2 or away therefrom, as may be required. The groove i^2 in the cam is made up of four parts—that is to say, two dwells and two throws, alternated. The dwells are on opposite sides of the cam and of equal duration, each extending nearly half-way around the cam. The throws are equal and on opposite sides of the cam, one, t^2 , Fig. 18, being to the right, and the other, u^2 , Fig. 34, to the left, both being of brief duration. From this description it will be understood that the action of the cam as it turns will be to push and pull the stem m^2 alternately through part n^2 of the carriage, holding it unmovable for a brief interval in each of its extreme positions. This is in case the threaded rings are turned sufficiently back, so as not to come in contact with the part n^2 . If, however, the rings be turned snugly against the part n^2 , as shown in Fig. 34, the endwise or longitudinal motion of parts resulting from the action of the cam will be transferred from the stem m^2 to the cutter-spindle W , causing the cutter to move from side to side, as indicated in Fig. 38, and in these endwise motions of the spindle the whole cutter-carrier N , with the cam and gear V and other dependent parts, participate.

I prefer to form the gear V and the coacting pinion y on the back shaft u with spiral teeth, as shown, though bevel-gears might be employed instead. By using spiral teeth the gear V may move laterally across the shaft u and pinion, as in making the sidewise motions of the cutter already described, without interfering with the harmonious action of the pair.

It is evident that if the rings be so located upon the stem that the distance between the pair exceeds the horizontal length of the part n^2 by the amount of the throw of the cam (leaving the space v^2 , Figs. 17 and 18) the cam will not act to move the cutter-spindle longitudinally. It will be understood, also, that if the width of the space v^2 is less than the throw of the cam the spindle will be

moved longitudinally by the cam to the extent of the difference between the width of said space and the throw of the cam. By means of the threaded rings, then, the extent of the sidewise motion of the cutter may be regulated at pleasure. The two rings p^2 and r^2 , adjacent to the part n^2 , are graduated, as shown, an index w^2 being provided for accurately reading the positions of these rings. The rings all turn independently of each other upon the stem, and in determining the lateral motions of the cutter in any given case the graduated rings are first set to their proper places on the stem and the outer rings then brought up snugly against them to keep them from turning, the pairs of rings in this respect acting as ordinary jam-nuts. The lead of the thread on the stem is made twenty to the inch, and the graduated rings are each divided into fifty equal parts, so that by turning either index-ring through the distance of one space will serve to regulate the lateral position of the cutter to the amount of one one-thousandth of an inch.

The rings are set in every case so the cutter will be moved sidewise by the cam through a space just equal to the width of the points of the teeth of the cutter, this being clearly indicated in Fig. 38. Cutters of different thickness or having teeth of different widths at the points are employed for forming different sizes of gear-teeth, and the sidewise throw of the cutter is regulated accordingly by means of the rings.

The cam-wheel h^2 is formed with internal teeth, as shown in Fig. 16, and driven by a pinion x^2 , Figs. 15 and 16, rigid with the cutter-spindle W . A free intermediate gear y^2 connects the pinion and the cam-wheel, giving to the parts what is known as "sun-and-planet" motion, the motions of the parts being indicated by the several arrows in Fig. 16. The gear y^2 has no fixed axis, but rolls freely around the pinion as the spindle W is turned by means of the gear V .

The pinion x^2 and gear V , Figs. 15 and 16, are splined onto the cutter-spindle W in the usual manner, the feather in the gear being shown at z^2 , both being held to place by a nut a^2 . (See Figs. 8, 14, and 19.)

The taper-arbor for the cutter a' , Fig. 15, is held firmly in the spindle W by means of an axial rod b^3 , threaded into the arbor, as shown.

The blank-gear spindle I , (shown in Fig. 21,) which turns freely within the spindle-barrel L , is formed to receive a taper-arbor X for holding the blank-gear K while teeth are being formed thereon. This arbor is formed with a reduced part c^3 at its outer end, having three, more or less, longitudinal slits d^3 , Figs. 28 and 29, which constitutes a seat upon which to receive the blank-gear. The arbor is hollow, the bore being slightly tapered or flaring in the seat c^3 , and an axial expander e^3 is provided within the arbor, having a tapered part f^3 to fill the tapered cavity

within the seat c^3 . An axial rod Y is provided within the spindle and receives within its inner end a threaded part g^3 of the expander for the purpose of drawing the latter inward in a manner to cause the divided seat c^3 to expand and so firmly press the bore of the gear to hold the latter securely upon the arbor. This affords a convenient method of holding the blank firmly to place while being 5
10 acted upon by the cutter and avoids the use of a nut or other device at the small end of the blank to hold the latter. When large gears are being cut in machines adapted for the purpose, the holding-arbor for the blank 15
15 may be extended and provided with an overhanging nut to hold the blank in place; but in cutting smaller bevels such a holding-nut would be in the way of the cutter as the latter comes out at the small ends of the teeth. 20
20 The arbor X is threaded upon its surface and provided with a threaded ring h^3 , Fig. 21, (see also Figs. 1, 14, 19, and 28,) in position to bear against the end of the spindle I . By turning the ring against the end of the 25
25 spindle when it is wished to remove the arbor the latter will be started out of the spindle, the holding-rod Y being first unscrewed from the expander e^3 . To turn the ring h^3 , it is provided with holes i^3 , with which to use a 30
30 spanner-wrench.

The spindle-carrier H , Figs. 1, 14, and 20, is secured to the segment G by means of clamp-bolts k^3 , their heads occupying the wide parts of the T-shaped circular slots h and g . The 35
35 inner side of the slot g is formed with teeth l^3 , and a pinion m^3 is provided to engage said teeth, the shaft of said pinion being held in a seat in the carrier H . The outer end n^3 of the pinion-shaft is squared for the purpose 40
40 of receiving a wrench or crank for turning the pinion. By this means the carrier H may be moved to any desired position upon the face of the segment G , its position in any given case being determined by the bevel of 45
45 the blank to be cut. This spindle-carrier is enlarged at o^3 and formed with a central transverse cavity or opening in which to receive a split ring Z , Figs. 1, 2, 14, 20, and 21, encircling the spindle-barrel L . The ring is 50
50 clamped upon the barrel by means of a threaded stud p^3 and handle r^3 threaded onto the stud, the stud crossing the slit s^3 in the ring. By tightening the ring at any time firmly 55
55 upon the spindle-barrel the latter and the spindle are prevented from having endwise motion in the spindle-carrier.

The spindle-barrel L is toothed along its under side, as shown at t^3 , Fig. 22, and a pinion u^3 (see also Fig. 2) is provided in the ring 60
60 Z to engage said teeth, by means of which the spindle-barrel and the spindle may be moved longitudinally in the spindle-carrier to move the blank-gear toward or from the cone-center of the machine and into position to be acted 65
65 upon by the cutter. The outer end v^3 of the pinion-shaft (see also Fig. 1) is squared for the purpose of receiving a wrench or crank

for turning the pinion. The spindle-barrel is formed with a longitudinal spline or groove of the usual kind appearing in Fig. 2, the 70
70 inner bore of the carrier H and the ring Z being provided with feathers to occupy said spline, the feather in the ring being shown at o^3 .

The spindle-barrel is formed at its upper or 75
75 outer end with a head A' , Figs. 1, 21, and 43, to which is secured a hanger w^3 (see also Figs. 20 and 23) for carrying the main parts of an indexing mechanism. The hanger holds a shaft x^3 in a plane at right angles to the axis of the 80
80 spindle, which shaft carries a worm y^3 in a recess formed in the hanger. The shaft is held in the hanger by means of a collar e^4 at one end and a screw p^7 , threaded in the opposite end, a washer r^7 being provided under the 85
85 head of the screw to bear against the end of the hanger. A worm-gear B' , rigid with the spindle, is engaged by the worm, the latter being central over the gear. The worm-gear is splined onto the spindle and held to place 90
90 by a threaded ring z^3 on the extreme end of the spindle, formed with holes a^4 for the purpose of the use of a wrench in turning it. The spindle, as shown in Fig. 21, is formed with an enlarged part at its right-hand end to bear 95
95 against the end of the spindle-barrel, and the worm-gear B' being held against the opposite end of the barrel prevents endwise motion of the spindle within the barrel. A yoke C' , 100
100 Figs. 1, 20, 23, 24, and 43, is adjustably secured to the hanger w^3 , as by a set-screw b^4 , which serves to carry gearing and other parts of the indexing mechanism.

Upon the outer end of the shaft x^3 and rigid therewith is placed a pinion c^4 , held to place 105
105 by means of a thumb-nut d^4 , the pinion being outside of the collar e^4 of the shaft. A detent-carrier f^4 has a part occupying the opening g^4 of the yoke and held to the latter by means of a threaded nut or ring h^4 , formed with circumferential openings i^4 for the use of a wrench. A shaft k^4 , central within the holder f^4 , serves to hold a gear l^4 in position to engage the pinion c^4 . The shaft has a journal-bearing in the holder f^4 and is held to place 110
110 by means of an end screw m^4 and washer. The gear turns with the shaft, and a crank n^4 , adapted to turn the shaft, is placed upon the latter outside of the gear and held to place by 115
115 a thumb-nut o^4 .

Now it will be understood that by turning the crank the worm y^3 will be turned and so the spindle I with the blank-gear K . The holder f^4 is provided with a chambered barrel p^4 , occupied by a detent r^4 , actuated by a 120
120 spring s^4 . The detent is parallel with the shaft k^4 , having its head slightly projecting from the end of the barrel to engage and hold a tooth t^4 rigid with the crank. (Clearly shown in Figs. 20 and 23.) The tooth t^4 is 125
125 opposite or on a line with the handle u^4 of the crank, the latter being extended across its axis and provided with another rigid tooth y^4 , similar to the tooth t^4 , in position to meet 130
130

the detent when the crank is turned half around. On account of the two teeth t^4 and y^4 the crank may be caught and held by the detent at every half-revolution.

5 A releasing-lever v^4 (see also Figs. 19 and 24) is provided by means of which the detent may be drawn within the barrel p^4 , thus releasing the crank. This lever is held to the detent by means of a pin w^4 , and it occupies 10 a shallow rectangular cavity x^4 in the end of the barrel, within which cavity the lever acts. The head of the detent is formed with a notch in which to receive a tooth of the crank, at either side of which notch the head is beveled 15 or inclined, so that when turning the crank and a tooth encounters the detent the latter will be pushed back against the spring and allow the tooth to glide into the notch. By loosening the nut h^4 the detent-holder f^4 may 20 be moved anywhere along the slot g^4 of the yoke for the purpose of changing the pinion c^4 , as may be required. The gear l^4 has sixty teeth and is constant, but pinions of different diameters are substituted for the pinion 25 c^4 , according to the number of the teeth to be cut upon the blank-gear K . As the machine is constructed with sixty teeth on the worm-gear B' , there will be formed as many teeth on the blank K as there are teeth on the 30 pinion c^4 , turning the crank through one complete revolution at each operation of indexing the blank.

Besides the rotary motion and the lateral recurrent motion given the cutter, as above 35 described, it, with all the parts resting upon the bracket or knee C , is given a horizontal circular reciprocating motion in the plane of its axis. The base-block P , with all of the superincumbent parts, is adapted to swing 40 horizontally upon the upper horizontal plain face z^4 , Fig. 9, of the knee. A circular V -shaped groove a^5 , Figs. 1, 8, 9, and 35, is formed in the upper face of the knee concentric with the shaft U , the under face of the base-block 45 being formed with a corresponding circular V -shaped ring or bead b^5 , Fig. 41, to occupy said groove. Headed studs c^5 c^5 , Figs. 9 and 41, projecting upward through slots d^5 in the knee and threaded into the base-block, hold 50 the latter in contact with the surface of the knee, but allowing it to swing freely thereon. An oscillating arm D' , Figs. 1, 8, 12, and 35, resting horizontally upon the upper end of the column A , is connected with the base-block P , preferably with a vertically-sliding joint—as, for example, a dovetail bearing e^5 . This manner of connecting the parts permits 55 of a vertical motion for the knee and base-block, while the arm retains its position on the column. The ordinary gib and set-screws z^5 are usually employed in the arm to coact with the bearing e^5 .

The column is formed with a horizontal race f^5 in its upper face, Figs. 1, 8, and 9, which 60 is occupied by a reciprocating bar or reciprocator g^5 , the upper surface of which is substantially in the plane of the upper surface of

the column. The reciprocator crosses the arm D' normally at right angles and is provided with a rigid vertical stud h^5 , Figs. 8 and 70 11, extending into a cavity i^5 in the arm. A block k^5 , fitting the stud with a journal-bearing, occupies said cavity in the arm, fitting the walls of the latter at two opposite sides, but leaving spaces at its opposite ends, so that 75 it may have a slight longitudinal motion in said oscillating arm. The cavity in the arm and contained parts are covered by a cap l^5 , (see also Fig. 35,) held to place by simple fasteners m^5 , threaded in the stud. 80

The bar g^5 is reciprocated by means of gearing within the column. (Shown in Figs. 3, 10, 12, and 13.) The column is formed with an opening or doorway A^2 through its side wall to render the parts within accessible, the 85 opening being closed by a door L' , Figs. 1, 10, and 19. E' is a rock-wheel having teeth part way around its circumference adapted to engage teeth n^5 on the under surface of the reciprocator. This wheel is rigid with a short 90 shaft o^5 , adapted to turn in a bearing p^5 , rigid with a wall of the column A , the shaft being held in place by an end screw r^5 . (See also Figs. 14 and 19.)

The driving-shaft S , Fig. 10, is provided 95 with a rigid pinion s^5 , which turns a gear t^5 , (see also Fig. 3,) rigid with a short shaft u^5 , journaled at t^6 and u^6 in the sides of the column, Figs. 3 and 25. Upon the shaft u^5 are placed loose companion pinions v^5 and w^5 , 100 which engage, respectively, twin gears x^5 and y^5 of one piece, Fig. 44, turning upon a horizontal stud or shaft F' , made rigid with the column. The shaft is held directly by a flanged bushing K' , (see Figs. 10, 14, and 44,) 105 secured to the column by simple means, as shown. The twin gear is formed with a transverse race a^6 , Figs. 3 and 10, in which a block b^6 is adapted to slide, so as to give the pin c^6 of the block a crank motion when the gear is 110 turned. A rod G' connects the gear with the wheel E' by being joined to the pin c^6 and the stud d^6 , rigid in the wheel. The pin being set nearer the center of the gear than the stud d^6 is to the center of the wheel, a revolution 115 of the former gear will cause the wheel to rock reciprocally and not revolve.

One or the other of the loose pinions v^5 w^5 on the shaft u^5 , Fig. 10, may be made to turn 120 with the shaft and drive the parts connected with it by means of a sliding key H' , (see Figs. 25 and 27,) reaching without the column, as shown in Fig. 14. This key, which always turns with the shaft, consists of a stem occupying an axial cavity m^6 in the end 125 of the shaft u^5 and adapted to slide longitudinally therein. The key is formed with a rigid part or bit n^6 , projecting outward through a slot o^6 in the side of the shaft. (See also Fig. 26.) The pinions, which are 130 side by side and in contact, are formed with an internal circular cavity p^6 , one-half in each, of such size in cross-section as to allow the projecting part n^6 of the key to pass freely

around therein without contact with either when the key is in the right position. Each pinion is further formed with an additional keyway or cavity v^6 , extending longitudinally 5 inward from the space p^6 , adapted to receive within it the projecting part of the key when the pinion is turned to the proper relative position. Now when the key occupies its central position, as shown in full lines in Fig. 10 25, no motion will be imparted by the shaft u^5 to either pinion; but should the key be pulled outward to the position shown by dotted lines at the right the pinion w^5 would be locked to the shaft and so turn with the latter and drive the twin gear and connected 15 parts, the pinion v^5 turning loosely or idling, or should the key be pressed inward to occupy the dotted position at the left the pinion v^5 would be locked to the shaft and become 20 a driver, the pinion w^5 idling. By these means the revolving of the driving-belt pulley R rotates the cutter z , reciprocates or swings it with various connected parts upon the knee C , as indicated by full and dotted 25 line positions in Fig. 35, and also moves the cutter in the line of its axis or tangentially to the periphery of the gear-blank being operated upon and radially relatively to the center of its swinging movement. The pinions v^5 and w^5 being of different diameters, as shown, the key not only serves to change the rate of the swinging motion of the cutter, but also to stop its swinging motion altogether. The driving-pulley also serves to 30 cause the blank-gear spindle to rock reciprocally in its bearings in the spindle-barrel, as described farther on.

The arm D' is formed with an upturned part e^6 , Figs. 1, 4, and 8, at its outer end, to 40 which is secured, by means of a clamp-screw f^6 , a rest or carrier g^6 , holding a horizontal toothed crown-segment h^6 , (see also Figs. 3, 6, 19, 30, and 35,) adapted to slide therein. The segment is also formed with teeth i^6 , Fig. 45 6, in its lower side within the carrier g^6 , and a traveling wheel k^6 (see also Fig. 5) is provided, formed with teeth at its upper side to engage the teeth i^6 of the segment. The wheel k^6 is adapted to turn upon a stud l^6 , 50 made rigid in the carrier g^6 , as clearly shown in Fig. 4. s^6 is a track upon which the blank part of the wheel is adapted to roll, secured to the column by means of a clamping-bolt x^6 . This track is vertically adjustable, usual 55 means (not shown and not involving invention) being provided for keeping its upper surface always level. The wheel and track are conical, all divergent lines running to the cone center of the machine, likewise the teeth 60 on both sides of the segment h^6 , and said segment with the track s^6 and the carrier g^6 for the segment are likewise curved concentric with the cone-center, as shown in the various figures. The segment h^6 rests in a circular 65 cavity in the upper surface of the carrier g^6 , inclined or dovetailed at the outside, as shown in Fig. 4, the inner face of the track bearing

against the part e^6 , near its upper end. The outer face of the upturned part e^6 of the oscillating arm D' is curved vertically concentric with said cone-center, as appears in Fig. 4, likewise the outer surface of the column A , against which the track s^6 bears. 70

The part e^6 of the arm D' is formed with a vertical slot v^6 , Figs. 4 and 12, for the clamping-bolt f^6 , and the track s^6 is formed with a vertical slot w^6 , Figs. 3 and 4, for the bolt x^6 , by means of which the various parts controlled by those bolts may be vertically adjusted. A vertical holding-screw y^6 , (see also Fig. 1,) threaded in a lug z^6 , projecting from the side of the column A , bears at its point against the lower face of the track s^6 , by means of which to assist in vertically adjusting it. 80 85

The outer face of the part e^6 of the oscillating arm is formed with a vertical groove a^7 , Fig. 12, and the carrier g^6 is formed with a corresponding vertical tongue b^7 , Figs. 8 and 35, to occupy the groove, on account of which 90 the carrier can have no other motion upon the arm than upward or downward.

From the foregoing description of the relation and the action of the parts it will be understood that as the oscillating arm D' swings 95 from side to side the wheel k^6 will roll along the track s^6 and cause the crown-segment h^6 to slide reciprocally in its bearings in the carrier g^6 . 100

I' , Figs. 1, 3, 4, 19, and 30, is a curved rocking arm connecting the crown-segment h^6 with the spindle-barrel L , above the spindle-carrier H . The lower end or foot of this arm is expanded and curved and formed with teeth to be engaged by the teeth on the upper 105 face of the crown-segment and adapted to roll therewith as the latter is reciprocated. (Clearly shown in Fig. 30.) The upper end of the rocking arm is joined to a ring N' , Figs. 1, 14, 19, and 20, secured to the spindle-barrel 110 L by a set-screw s^7 . By these means the reciprocations of the crown-segment cause the blank-gear K to reciprocally rock or turn upon its axis through short arcs of a circle. If the wheel k^6 were to roll uninterruptedly upon 115 the track s^6 , the segment, it will be understood, would move in each direction through a distance twice that which the wheel rolls upon the track or approximately twice the distance through which the outer end of the 120 arm D' swings. This extreme travel of the segment is provided to meet the requirements of any case that may occur in forming teeth on gears of all diameters within the limits of the machine and degrees of bevel; but it 125 would turn the blank-gear through a larger arc of circle than usually necessary to give the teeth formed upon the blank the desired form of cross-section.

To regulate the extent of the travel of the 130 crown-segment, and consequently the rocking of the blank-gear, arresters c^7 , Figs. 3, 5, 6, and 30, are provided for the wheel k^6 . These arresters are flat tapered pieces, each

having a broad plain foot or base d^7 extending across in front of the edge or tread of the wheel, as shown in Fig. 5. The flat bases d^7 of the arresters are tangent with the wheel 5 and adapted to meet and slide upon the track, as shown in dotted positions in Fig. 30, as the wheel rolls to the right or to the left. These arresters lap upon each other at their small ends and are held to turn upon an axial pin 10 e^7 in the stud l^6 of the wheel. (See Fig. 4.) Clamping thumb-screws f^7 are provided to hold the arresters in their positions of adjustment. These screws are threaded into blocks 15 g^7 , Fig. 5, in a circular dovetailed groove h^7 in the side of the wheel, the blocks being inserted through an opening l^7 , Fig. 6. When the wheel rolls in either direction upon the track—as, for instance, toward the right, as shown in Fig. 30—the foot of the arrester on 20 that side will be brought down flat upon the track and stop the rolling motion of the wheel and cause the latter to slide thence to the end of its motion in that direction.

While the wheel is rolling the crown-segment h^6 will move, as has been stated, twice 25 as rapidly as the axis of the wheel; but the moment the arrester begins to act and causes the wheel to slide the segment will then move simply as the wheel moves and no faster than 30 its axis and the carrier g^6 . The wheel is graduated on its face under the arresters, as shown, the zero-mark being vertically downward, for instance, when the segment is centrally within the carrier and the arm I' vertical, as appears in full lines in Fig. 30. The 35 graduation-marks are read alike each way from zero and at the knife-edges v^7 of the arresters. If the arresters are, to illustrate, turned back out of the way, so as not to touch 40 the track during the rollings of the wheel, the crown-segment will be given its maximum or extreme motion or throw and cause the blank-gear to roll through a large arc of circle. On the other hand, if the arresters are 45 both brought down to the zero-line the wheel will not roll at all, but slide in either direction as the oscillating arm D' swings to the right or to the left, thus giving the segment its minimum throw or travel and turning the 50 blank but little. Any extent of motion between these two extremes may be given the segment by setting the arresters nearer to or farther from the zero-line, and in practice the arresters are set so as to cause the blank-gear 55 to reciprocate through an angular distance equal to the angular distance between adjacent teeth being formed on the blank-gear at the pitch-circle.

An inspection of Fig. 30 will make the relative motions of the parts clear. If the parts are, to illustrate, in normal positions, as shown in full lines in the figure, and a motion of the oscillating arm D' sets in toward the right, the rolling of the wheel will bring the right-hand arrester down onto the track, as appears in dotted position c^8 . During this movement the wheel will advance to the position shown

by dotted lines k^8 , carrying with it the crown-segment to the dotted position h^8 and the rocking arm to the position in dotted lines at 70 I^8 . The continued motion of the oscillating arm, which has yet some distance to travel before its swing in that direction is completed, will cause the wheel and the arrester to slide to the respective dotted positions k^9 and c^9 , 75 the segment and rocking arm assuming the respective positions h^9 and I^9 . (Shown in dotted lines.) These relative motions of the parts, it will be understood, also take place in an opposite direction when the arm D' is 80 swung toward the left. These continued motions of the crown-segment and rocking arm in opposite directions after the wheel begins to slide serve to bring the faces of adjacent teeth alternately to the vertical plane k^7 , Fig. 85 38, hereinbefore described.

The graduated spaces upon the wheel are not made with reference to the degrees of a circle of the diameter of the wheel, but each major space covers a degree of a circle whose 90 center is, say, at the cone-center of the machine, with radius reaching to the outer end of a tooth of the crown-segment, so that by setting the arresters to the marks upon the wheel, as shown in Fig. 45, the extent of 95 travel of the crown-segment may be regulated in amounts corresponding to fourths of a degree of said large circle.

The cutter is set by means of the screw E for controlling the knee C , so that the points 100 of its teeth touch at its upper side a horizontal plane O' , Fig. 33, passing through the cone-center, and in setting the blank-gear the latter is brought in position, so that the line of the root of a tooth or the bottom of a space 105 between adjacent teeth coincides with said plane. The face of the circular segment G , Fig. 1, is graduated or marked in degrees of a circle and the spindle-carrier H or holder for the blank-gear is set in any given case 110 with reference to this scale on the segment, the figures being read at f^7 at the upper side 115 of the carrier. Rocking arms I' of different lengths are provided to be inserted in the machine, according to the position of the carrier 120 H upon the segment. Each arm when put in place is secured rigidly to the ring N' by means of the bolt u^7 , the curve of the toothed 125 foot of the arm being regulated according to the length of the arm, or, more accurately, the angular distance between the axis of the spindle and the crown-gear segment. The vertical adjustments of the segment-carrier g^6 and track s^6 , heretofore described, render but few arms I' necessary, as such adjustments meet the requirements of many kinds and sizes of blank-gears.

The connection between the oscillating arm D' and the blank-gear spindle is positive, rendering the rocking of the gear positive with 130 the swinging of the cutter.

The gear Y , Figs. 19 and 31, is adapted to slide longitudinally upon the shaft u , the latter being splined, as shown, and the gear be-

ing supplied with an ordinary feather occupying the spline. The shaft has no endwise motion, and the hanger or bearing x , which contains and controls said gear, being secured to the carriage O causes the gear to slide one way or the other upon the shaft as the carriage is moved upon the base-block.

The cutter-carrier N , Figs. 1 and 8, rests in a dovetail bearing in the carriage O , along which it is adapted to slide. The rocking of the gear and the swinging of the cutter will not give the faces of the teeth of the gear the correct form, another motion of the cutter being necessary—namely, the sidewise motion or thrust of the cutter, hereinbefore fully described, and shown in Fig. 38. The cam h^2 , which produces these sidewise motions or thrusts of the cutter, is timed to turn through one revolution while the cutter makes four revolutions, and the thrusts of the cutter are also timed with reference to the rocking of the blank-gear and the swinging of the cutter—that is to say, a side thrust of the cutter is made every time the blank-gear rocks in either direction, and consequently every time the cutter swings to one side or the other, the side thrusts being made quickly at the terminations of the swingings of the cutter. On account of these motions one side and then the other of the cutter acts on the opposing faces of two adjacent teeth of the blank-gear. These sidewise motions of the cutter are made accurately with reference to a vertical plane passing through the cone-center v^7 , Fig. 37. (Represented by the dotted line k^7 in Fig. 38.) In one position of the cutter the corners l^7 of the points of the teeth coincide with the plane, while in the other position of the cutter the other corners m^7 of the points of the teeth coincide with the plane, this plane, be it understood, not being fixed, but partaking of the swinging motion of the cutter. Each side of the cutter shapes a side of the tooth, and the cutter may be just wide enough to come through the small end of a space between teeth.

On account of the motions given the cutter it will finish the teeth of a bevel-gear with one setting of the machine, using only one cutter, a single revolution only of the gear being necessary to finish the teeth.

On account of the upper face z^4 of the knee C being horizontal and all the parts resting thereon moving horizontally when being swung by the reciprocating bar g^5 the swinging motions of the machine are easy, and these reciprocations of the parts may be made rapidly without any shock or jar to the machine.

It will be observed that in this machine what the cutter really does in successively passing through the blank is to accurately form the spaces in the face of the blank. Each space is formed by the cutter (which is single and solid) passing once through, and the spaces being correctly formed results in correctly-formed teeth. The machine does

not in any instance form both sides of a tooth simultaneously or while the cutter passes once through the blank, but, rather, both side walls and the bottom of a space between two teeth are completed each time the cutter passes through.

The relative positions of the cutter z and a gear-tooth w^7 being formed, resulting from the rocking of the gear and the simultaneous swinging of the cutter, are shown in Fig. 36. When both are at the extreme left, for example, the cutter is acting at the root of the tooth, and as both move toward the right (the cutter swinging and the gear rocking) the tooth will rock across the face of the cutter, the latter finishing at the point of the tooth, as shown by dotted lines w^7 and z at the right. The side thrust of the cutter now taking place toward the right brings the opposite side of the cutter l^7 against the other wall of the space or face of the adjacent tooth x^7 , near its root, and as both tooth and cutter now return to the left the former will rock across the face of the cutter from root to point. An opposite sidewise motion or thrust of the cutter taking place at this juncture brings the cutter and the tooth w^7 again into the positions shown at the left in the figure. Thus the cutter shifts quickly and frequently from one side wall of the space to the other, (or from the face of one tooth to the opposing face of the adjacent tooth,) doing a little work upon each alternately as the feed gradually carries the cutter along from the large end to the small end of the space.

The two extreme positions of the cutter assumed on account of its swinging motions are shown by full and dotted lines in Fig. 37. In this figure the cutter is shown as in a neutral position, so far as the side thrusts are concerned, the middle plane of the cutter passing through the cone-center v^7 .

This machine is adapted to cut the parallel teeth of spur-gears as well as radial or tapered teeth of bevel-gears. To cut the teeth of spur-gears, the spindle-carrier H is brought down to the zero-line, reading at the upper edge of the carrier, as in other cases. In this position of the parts the axis of the blank-gear spindle will be horizontal and intersect the axis of the shaft U at right angles. The cutter is lowered to bring the plane of the points of its teeth at the upper side to coincide with the line at the bottom of a space between teeth. In cutting spur-gears the latter are not rocked on their axes and the cutter is not swung or moved laterally by the cam, the cutter having no motion other than the rotary and the feed motion. For this parallel-tooth work the cutter is set so that its central vertical plane coincides with the plane k^7 , Fig. 38, the feed motion of the cutter being toward the cone-center along said plane. In this work the cutter needs to be formed with curved sides and of the right thickness to give the spaces in the blank-gear a correct form of cross-section. None of the

parts of the machine used for cutting radial teeth are in the way or have to be removed for cutting parallel teeth. The key H' , controlling the companion pinions in the column, 5 is set so as to clear both pinions, and the pairs of threaded rings on the stem m^2 are turned back, so as to not encounter the carriage O . This prevents the swinging motion and the side thrusts of the cutter and the 10 rocking of the gear.

In using this machine the blank-gears, whether conical or cylindrical, are first turned to the proper size and shape, the surface to be cut corresponding with the points of the 15 teeth.

For cutting a bevel-gear, for instance, the blank is mounted upon the blank-gear arbor and the blank-gear carrier H is moved upon the segment G until the root angle of the blank 20 is read at f' on the carrier. The root angle of a gear is the angle between the axis of the gear and the line of the bottom of a space between adjacent teeth. The blank-gear spindle is then moved endwise until the root-line of a tooth passes through the cone-center 25 of the machine. The cutter is adjusted vertically, so that the point of a tooth at the top coincides with the root-line, and adjusted laterally, so that one side—say the right side, Fig. 30—38—of the points of its teeth will be in a vertical plane k^7 , passing through the cone-center. Now set the jam-nuts $o^2 p^2$, Figs. 8 and 18, up against the part n^2 of the carriage O 35 and bring the other pair of jam-nuts or threaded rings $r^2 s^2$ so that the space v^2 shall equal the difference between the throw of the cam and the thickness of a point of a tooth. Set the arresters for the traveling wheel k^6 , 40 Fig. 30, so that the distance between them is equal in degrees (as marked on the wheel) to the width in degrees at the pitch-line of a space to be cut in the blank-gear. Set the crank-pin c^6 , Fig. 3, of the twin gears in the column to give the cutter a swing sufficient 45 to clear the cut. Put into the machine a rocking arm I' of proper length and vertically adjust the crown-segment h^2 so its upper teeth will properly engage the teeth of the rocking arm. The rate of the feed is regulated by moving the feed-ring s' , Fig. 8, toward or from the axis of the feed-shaft, according to the material of which the blank-gear is made and the size of the cross-section 55 of the space between teeth. In cutting the spaces of steel blanks the feed needs to be much slower than when cutting the spaces in blanks of cast-iron or other softer material.

The sidewise motion or thrust of the cutter is in every case, as has been already stated, 60 equal to the width of the point of a tooth of the cutter. As a matter of convenience I form the cam-wheel with an ultimate throw of one-fourth of an inch, which is the width of the points of the teeth of the widest cutter 65 used in the machine. Then in setting the pairs of adjusting-rings in any given case the

space v^2 between either pair and the intermediate stop-piece n^2 of the carriage O is made equal to one-fourth of an inch minus the thickness of the point of a tooth of the 70 cutter.

What I claim as my invention is—

1. In a machine for forming the teeth of gears, the combination with a gear-blank holder, of a cutter, and means for simultaneously moving the cutter circularly and tangentially relatively to the periphery of the gear-blank, substantially as set forth. 75

2. In a machine for forming the teeth of gears, the combination, with a gear-blank holder, of a cutter, and means for simultaneously moving the cutter circularly, tangentially, and radially, substantially as set forth. 80

3. In a machine for forming the teeth of gears, the combination with a gear-blank holder, of a cutter movable circularly, tangentially, and radially, and means for varying the circular movement relatively to the radial movement while the tangential movement remains the same, substantially as set forth. 85

4. In a machine for forming the teeth of gears, the combination, with a gear-blank holder, of a cutter, and means for moving the holder axially, and means for moving the cutter circularly and tangentially relatively to the periphery of the gear-blank, substantially as set forth. 90

5. In a machine for forming the teeth of gears, the combination, with a gear-blank holder, of a cutter, and means for moving the holder axially, and means for moving the cutter circularly, tangentially, and radially, the tangential movement being relatively to the periphery of the gear-blank and the radial movement being relatively to the circular movement, substantially as set forth. 100

6. In a machine for forming the teeth of gears, the combination, with a gear-blank holder, of a cutter, and means for moving the cutter circularly, and tangentially, the tangential movement being recurrent relatively to the periphery of the gear-blank, substantially as set forth. 110

7. In a machine for forming the teeth of gears, the combination, with a gear-blank holder, of a cutter, and means for moving the cutter circularly, tangentially, and radially, the tangential movement being recurrent, 120 and the circular movement varying in extent relatively to the radial movement, substantially as set forth. 115

8. In a machine for forming the teeth of gears, the combination, with a gear-blank holder, of a cutter, and means for simultaneously moving the cutter circularly and tangentially, and stops for limiting the amount of tangential movement, substantially as set forth. 125

9. In a machine for forming the teeth of gears, the combination, with a gear-blank 130

holder, of a cutter, and means for moving the cutter toward and from the holder at right angles to the point of the tooth to be cut, and means for moving the cutter circularly and tangentially relatively to the periphery of the gear-blank, substantially as set forth.

10. In a machine for forming the teeth of gears, the combination, with a gear-blank holder, of a cutter, means for moving the cutter toward and from the holder at right angles to the point of the tooth to be cut, and means for moving the cutter circularly, tangentially, and radially, the tangential movement being relatively to the periphery of the gear-blank, and the radial movement being relatively to the circular movement, substantially as set forth.

11. In a machine for forming the teeth of gears, the combination, with a gear-blank holder, of a swinging base-block pivotally secured adjacent thereto, a cutter-support mounted upon the block and movable at a tangent to the periphery of the gear-blank, and means for simultaneously moving said block and cutter-support, substantially as set forth.

12. In a machine for forming the teeth of gears, the combination, with a gear-blank holder, of a swinging base-block pivotally secured adjacent thereto, a cutter-carrier mounted upon the block and movable tangentially to the periphery of the gear-blank, and a cutter-spindle in the carrier, substantially as set forth.

13. In a machine for forming the teeth of gears, the combination, with a gear-blank holder, of a swinging base-block pivotally secured adjacent thereto, a carrier mounted upon the block to move tangentially to the swinging movement of the block, a projection upon the carrier, a stem movable longitudinally through said projection, stops upon the stem, a spindle in the carrier, and means for moving said stem, substantially as set forth.

14. In a machine for forming the teeth of gears, the combination, with a gear-blank holder, of a swinging base-block pivotally secured adjacent thereto, a carrier mounted upon the block, a cutter mounted on the carrier, a longitudinally-movable stem adjacent to the carrier and adapted to engage therewith, a cam-wheel adjacent to one end of the stem provided with a groove for moving the stem, said groove being provided with two throws and two dwells, substantially as set forth.

15. In a machine for forming the teeth of gears, the combination, with a gear-blank holder, of a rotary cutter movable circularly, tangentially, and radially, and means for simultaneously stopping the rotary, tangential and radial movement of the cutter, substantially as set forth.

16. In a machine for forming the teeth of gears, the combination, with a gear-blank holder, of a radially-movable rotary cutter,

and means for rocking the holder axially at variable rates of speed, substantially as set forth.

17. In a machine for forming the teeth of gears, the combination, with a gear-blank holder, of a laterally-movable cutter, an arm for locking the holder axially, and means for moving the free end of said arm at different rates of speed, substantially as set forth.

18. In a machine for forming the teeth of gears, the combination, with a gear-blank holder, of a swinging base-block pivotally secured adjacent thereto, a cutter upon the base-block, an arm connected with the blank-holder, a wheel connected with the base-block for moving the arm, and means for locking the wheel against rotation during a portion of the swinging movement of the base-block, substantially as set forth.

19. In a machine for forming the teeth of gears, the combination, with a gear-blank holder, of a swinging base-block pivotally secured adjacent thereto, an arm for moving the block, a wheel upon said arm, an arm connected with the blank-holder, a rack between the end of the blank-holder arm and the wheel, and means for locking the wheel against rotary movement during a portion of the swinging movement of the arm on the base-block, substantially as set forth.

20. In a machine for forming the teeth of gears, the combination with a gear-blank holder, of a base-block pivotally secured adjacent thereto, an arm for swinging the block, the free end of which is provided with a wheel, a track for the wheel, an arm connected with the blank-holder, a rack between the end of the blank-holder arm and the wheel, and arresters adjustably secured to the wheel and adapted to engage with and slide upon the track, substantially as set forth.

21. A machine for forming the teeth of gears, having a rotary cutter adapted to move sidewise in the line of the axis of its rotation, and means to give it said sidewise motion, and a feed motion for the cutter, in combination with a holder for the blank-gear, and means for rocking the latter, said sidewise motions of the cutter being timed with reference to the rocking of the gear, said motions being automatically variable relatively to each other, substantially as described.

22. A machine for forming the teeth of gears, having a rotary cutter adapted to move sidewise in the line of the axis of its rotation, and means to give it said sidewise motion, and a feed motion for the cutter, in combination with a holder for the blank-gear, and means for reciprocally swinging the cutter and for rocking the blank-gear upon its axis, the said sidewise motion of the cutter being made at the termination of each swing of the cutter, substantially as shown and described.

23. A machine for forming the teeth of gears, having a rotary cutting-tool adapted to have sidewise motion in line with the axis of its rotation, and means to give it said side-

wise motion, in combination with a holder for the blank-gear to be acted upon by the cutter, and a feed motion for the cutter, and means for micrometrically adjusting or regulating the extent of said sidewise motions of the cutter, substantially as set forth.

24. A machine for forming the teeth of gears, having a cone-center, and a rotary cutter and feed mechanism therefor, in combination with a holder for the blank-gear to be cut, and means for turning said gear upon its axis, and to alternately move the cutter in parallel positions from one side to the other of a plane at right angles with the axis of the cutter and passing through the cone-center of the machine, substantially as described.

25. A machine for forming the teeth of gears, having a spindle for holding the gear to be cut, a spindle-barrel, and a holder for both spindle and spindle-barrel, in combination with a clamping-ring carried by said holder to control the spindle-barrel, and means for moving the spindle-barrel longitudinally through said holder, substantially as set forth.

26. A machine of the class described, a column, a reciprocating bar at the top of the column, a frame pivotally secured at an angle to the bar, a revolving cutter on the frame movable toward and from the pivotal point, and means for connecting the bar with the frame whereby the frame is swung upon its axis as the bar is reciprocated, substantially as set forth.

35 27. A machine of the class described having a prismatic column for supporting the operating parts, formed with a horizontal upper surface and with a horizontal race therein, in combination with a reciprocating bar or reciprocator occupying said race and adapted to slide therein, with means to give said bar a rectilinear reciprocal motion in the race, substantially as shown and for the purpose specified.

45 28. A machine of the class described, a column, a reciprocating bar at the top of the column, a frame pivotally secured adjacent to the bar, and means for connecting the bar and the frame so that when the bar is reciprocated the frame is moved upon its pivot, a revolving cutter movable toward and from the pivotal point of the frame, a gear-blank holder above the cutter, and an arm connected with the holder at one end and adjustably connected with the frame at the other, and means for simultaneously moving said bar, arm and holder, substantially as set forth.

29. A machine for forming the teeth of gears, having a circular segment mounted upon a base, and a holder for the blank-gear to be cut secured movably to said segment, a spindle-barrel in said holder, a spindle in said barrel, and a blank-gear arbor secured to said spindle, with a rack and pinion to move said holder and dependent parts along the segment, substantially as specified.

30. A machine of the class described, a gear-

blank holder, a spindle therein, one end of which is provided with means for holding the gear-blank and the opposite end is provided with a worm-gear, a worm for operating said gear, a yoke secured to the holder, a toothed wheel adjustably secured in the yoke provided with as many teeth as there are teeth in the worm-gear, and a removable wheel upon the end of the worm for determining the number of teeth of the gear upon the spindle, substantially as set forth.

31. A machine of the class described, a gear-blank holder, an arm secured thereto, the free end of which is provided with a segmental gear, a segmental rack for engaging therewith, a track below the rack, a laterally-movable frame provided with a rotary cutter, and means for moving the cutter thereon, a wheel upon the frame, a portion only of the periphery of which is provided with teeth to engage with the rack, and stops adjustably secured to the wheel for limiting its rotation upon the track, substantially as set forth.

32. A gear-tooth-forming machine, having a supporting-column, a knee or bracket at one side of the column, a base-block adapted to swing upon the knee, and a cutter supported by the base-block, in combination with an oscillating arm connected with said parts upon the knee and resting upon the column, and means to reciprocate said arm and parts above the knee, substantially as shown and described.

33. A gear-tooth-forming machine having a supporting-column, a knee or bracket held by the column, a vertical shaft held by the column and the knee, a base-block upon the knee, and a cutter supported by the base-block, in combination with an oscillating arm on the column connected with the base-block, and means to reciprocate said arm and base-block around the axis of said shaft as a center, substantially as specified.

34. A machine for forming gear-teeth, having a supporting-column, a knee held by the column, a vertical geared shaft held by the column and the knee, a base-block on the knee, a horizontal geared shaft at the side of the base-block, a shaft in the base-block connecting said vertical shaft and said horizontal shaft, in combination with a cutter, and a cutter-spindle supported by the base-block, and gearing connecting said spindle and said horizontal shaft, and means to turn the vertical shaft, substantially as set forth.

35. A machine of the kind described, a column provided at its top with a segmental upright, a holder adjustably secured thereto and provided with a split sleeve, a toothed spindle-carrier in the holder, a pinion journaled in the sleeve in engagement with the carrier, and a locking-bolt through the split portion of the ring for clamping the carrier in its adjusted position, substantially as set forth.

36. A machine for forming gear-teeth, having a supporting-column, a base-block supported by the column, a carriage on the base-

block for supporting a cutter, a feed-screw for the carriage, a feed-shaft to coact with the feed-screw, provided with a disk at one end, a back shaft at right angles to the axis of the disk, a friction-ring on the back shaft movable across the face of the disk, a holder for said shaft, pivoted so as to allow the shaft motion toward or from the feed-screw and the back shaft, and means for controlling said holder, substantially as described.

37. In a machine for forming the teeth of gears, a cutter-carrier, a carriage for holding the cutter-carrier, a spindle in the carrier, an internally-toothed cam free on the spindle, a pinion on the spindle to turn the cam, an intermediate gear for the pinion and the cam, a block or body actuated by the cam, a stem in the block or body occupying a place in said carriage, and stops to control said stem whereby the cam acts to move the spindle-carrier upon the carriage, substantially as and for the purpose set forth.

38. In a machine for forming gear-teeth, having a supporting-column, a movable bracket held by the column, parts for supporting a cutter resting upon the bracket and adapted to swing thereon, an oscillating arm upon the column connected with the parts supporting the cutter, means for reciprocating said arm, a segment-carrier secured to said arm, a toothed segment held by said carrier, a toothed wheel held by the carrier to engage said segment, and a track for said wheel to roll upon, substantially as and for the purpose specified.

39. In a machine for forming gear-teeth, having a supporting-column, a movable bracket held by the column, parts for supporting a cutter resting upon the bracket and adapted to swing thereon, an oscillating arm upon the column connected with the parts supporting the cutter, means for reciprocating said arm, a segment-carrier secured to said arm, a toothed segment held by said carrier, a toothed wheel held by the carrier to engage said segment, and arresters for controlling said wheel, as described.

40. In a machine for forming gear-teeth, having a supporting-column, and a rotary cutter, an oscillating arm upon the column for actuating said cutter, a segment-carrier secured to the arm, a toothed segment on said carrier, a toothed wheel held by said carrier to actuate the segment, a blank-gear spindle, and parts connecting said spindle and the toothed segment, substantially as shown and described.

41. In a machine for forming the teeth of gears, the combination, with a support, of a base-block pivotally secured thereto, a gear-blank holder above the block, a motor-shaft journaled at the pivotal point of the block, a cutter upon the block movable tangentially relatively to the periphery of the gear-blank and radially relatively to said pivotal point,

and means connected with said motor-shaft for moving the cutter simultaneously in said directions in all positions of the block around its pivot, substantially as set forth.

42. In a machine for forming the teeth of gears, the combination, with a support, of a base-block pivotally secured thereto, a gear-blank holder above the block, a motor-shaft journaled at the pivotal point of the block provided with a gear-wheel, a rotary cutter upon the block, mechanism for rotating the cutter, moving it tangentially relatively to the gear-blank and moving it radially relatively to the pivotal point, a shaft for operating said mechanism the inner end of which is provided with a gear in engagement with the gear on the motor-shaft, and means for swinging the block around its pivotal point, substantially as set forth.

43. In a machine for forming the teeth of gears, the combination, with a support, of a base-block pivotally secured thereto, a motor-shaft journaled at the pivotal point of the block, a rotary cutter on the block, two parallel shafts, one of which rotates the cutter and the other one moves it radially relatively to the pivotal point of the block, mechanism for operating said shafts, and a shaft for communicating motion from said motor-shaft to said mechanism in all positions of the block around its pivotal point, substantially as set forth.

44. In a machine for forming the teeth of gears, the combination, with a support, of a base-block pivotally secured thereto, four shafts rectangularly arranged relatively to each other, one of said shafts being a feed-screw, a cutter upon one of the other shafts, a friction-disk and a friction-ring upon the other shafts, and means for operating said shafts from a common source of power, substantially as set forth.

45. In a machine for forming the teeth of gears, the combination, with a gear-blank holder, of a rotary cutter provided with two oppositely-located cutting-faces, and means for automatically and reciprocatingly moving said cutter in the line of its axis between two adjacent teeth of the blank being cut, substantially as set forth.

46. In a machine for forming the teeth of gears, the combination with a gear-blank holder, of a rotary cutter provided with two oppositely-located cutting-faces, and means for reciprocatingly moving said cutter in the line of its axis simultaneously with the forward feeding movement of the cutter, substantially as set forth.

In witness whereof I have hereunto set my hand, this 17th day of February, 1897, in the presence of two subscribing witnesses.

JAMES E. GLEASON.
